(57) **CLAIM**

The ornamental design for a housing for a communication system, as shown and described.

DESCRIPTION

FIG. 1 is a front and right side perspective view of housing for a communication system showing my new design; FIG. 2 is a front and left side perspective view thereof; and, FIG. 3 is a bottom perspective view thereof.

The broken lines shown in FIG. 3 represent environment and are for illustrative purposes only and form no part of the claimed design.

1 Claim, 3 Drawing Sheets

FIG. 1

FIG. 2

FIG. 3
